UNITED STATES PATENT OFFICE.

DANIEL KOPS, OF NEW YORK, N. Y.

APPAREL-CORSET.

1,366,190.

Specification of Letters Patent. Patented Jan. 18, 1921.

Application filed April 26, 1920. Serial No. 376,486.

To all whom it may concern:

Be it known that I, DANIEL KOPS, a citizen of the United States, residing in the borough of Manhattan, city, county, and 5 State of New York, have invented an Improvement in Apparel-Corsets, of which the following is a specification.

This invention relates to an apparel corset and more particularly to that type of 10 corset garment in which in the front portions thereof adjacent the front steels there are employed tension straps so formed and placed in the garment as to produce a flattening effect at the waist line of the wearer, 15 thus tending to cause the upper portions of the front steels to extend away from the body of the wearer and at the same time providing a support for those portions of the body of the wearer lying beneath the 20 garment and between the waist line and the groin. I am aware that heretofore apparel corsets have been constructed in this manner as, for example, shown and described in Letters Patent No. 1,328,675, granted to me 25 January 20, 1920. In this type of garment, however, particularly when the opposite sides of the tension straps are permanently connected in the garment, there is a tendency in the overlying body portion of the 30 garment to wrinkle, due to the fact that the tension strap is necessarily shorter than the overlying part of the garment, considered circumferentially, and obviously to avoid this wrinkling effect the tension strap in use 35 must be extended or stretched to at least the equal length of the overlying parts of the body of the garment. The object of the present invention is to overcome this difficulty as well as to provide a means in the 40 corset garment of causing the lower edge of the tension strap to fit into the groin of the body of the wearer and to cause a continued flattening effect from the waist line to the lower edge of the garment which, in 45 view of the fact that the garment is provided with a skirt, extends substantially from the waist line to the knee of the wearer, at the same time causing a flattening effect at the thigh of the wearer. In order to 50 accomplish this result, I employ a hose supporter strap connected to the body of the garment above the lower edge of the tension strap and extending downwardly to approximately the lower edge of the garment 55 where a hose supporter is connected thereto as well as to the adjacent lower edge of the

garment for accomplishing the purposes described. I am furthermore aware that heretofore various forms of hose supporter straps have been employed in apparel corsets, but as far as the same have come to my knowledge, in no instance has a hose supporter strap been used to accomplish the purposes to which I have hereinbefore referred. 60

65

In the drawing:

Figure 1 is a perspective view illustrating a corset made in accordance with my present invention.

Fig. 2 is an enlarged plan of the front 70 portion of a corset showing the inner side thereof and illustrating the construction to which the present invention relates, and

Fig. 3 is an enlarged cross section taken on line 3—3, Fig. 2. 75

Referring to the drawing, it will be seen that in carrying out this invention the corset garment as is customary comprises a body member 10 which at the front or forward edge is fitted with steels 11 having 80 clasps 12 by which the steels may be connected, and also the body of the garment is preferably provided with a depending skirt indicated at 13 and extending continuously to the front edge of the corset. 85

In this corset I employ a tension strap 14 of elastic material. This, as illustrated, is preferably triangular in outline and is secured in the garment with the base or longer side thereof attached to the front 90 steel section adjacent the front steels along a line of stitching indicated at 15. The opposite edge of the tension strap is, as illustrated, secured to the body of the garment distant from the front steels along a line of 95 stitching indicated at 16 which preferably also includes the stitching or a part thereof for inclosing a stay or corset stiffener, while the upper and lower edges of the tension strap are free from attachment to the body 100 of the garment. It will be obvious, however, that the tension strap may be connected to the body of the garment in any suitable manner without departing from the nature and spirit of this invention. 105 Furthermore, the function of this tension strap placed as hereinbefore described is, when the garment is in position on the body of the wearer, to effect a flattening at the waist line, thereby tending to force the upper ends of the corset steels outwardly away 110 from the body of the wearer and also to act

as a support for those portions of the body of the wearer underlying the garment and extending from the waist line to the groin.

In this invention I also employ a hose 5 supporter strap 17. As illustrated, this depending hose supporter strap is connected to the body of the garment along a line of stitching indicated at 18 which is appreciably above the lower end of the tension 10 strap 14 so that the upper end of the hose supporter strap underlies the lower edge of the tension strap and assumes a position between the same and the corresponding portions of the body of the garment, with this 15 upper edge of the hose supporter strap extending between the attached edges of the tension strap. The hose supporter strap is also connected to the body of the garment along the edge thereof distant from the 20 front steels as indicated at the line of stitching 19 which is preferably a continuation of the line of stitching 16, while the opposite edge 20 of the hose supporter strap is entirely free from attachment to the garment. 25 The edge of the hose supporter strap distant from the front steels is attached to the body of the garment and the skirt thereof along the line of stitching 19 as hereinbefore described, which, however, terminates at a 30 point 21 an appreciable distance above the lower edge of the skirt so as to provide an extension of the hose supporter strap indicated at 22 which terminates at substantially the lower edge of the skirt. I also employ a 35 hose supporter indicated at 23 with the upper end thereof divided as indicated at 24 and 25, with the former division connected to the lower edge of the skirt and the latter to the end of the extension 22 of the depending hose 40 supporter strap. In the front of the garment I may also provide a hose supporter 26, and as illustrated the upper edge of the garment may be fitted with an insert of yielding material as indicated at 27 placed therein adjacent the upper end of the front steel and 45 extending a predetermined distance therefrom.

In the use of the garment as hereinbefore described and as will now be apparent, the 50 tension strap 14 extending from a point above the waist line to the lower edge of the body of the garment will overlie the waist line at the front thereof and extend to the 55 groin section of the wearer. In so doing, when the tension is applied thereto, the effect of the strap at the waist line is to produce a flattening thereof at the same time causing the upper edges of the corset steels to extend away from the body of the wearer 60 and to also provide a support for the body or those portions thereof underlying the strap and extending from the waist to the 65 groin. If, however, the tension applied to the strap is not sufficient to extend the same so that its length will be at least equal to

the length of the overlying parts of the body of the garment there will be a wrinkling effect in this overlying portion of the corset body. This effect is overcome by the tension applied by the hose supporters to the hose 70 supporting strap pulling this portion of the body of the garment downwardly to remove any wrinkles that there may be made therein, and also to cause the lower end of the tension strap to fit into the groin of the 75 wearer so that a continuation of the flattening effect at the waist line is produced which extends from the waist line to the lower edge of the garment. This obviously also has the effect of producing a desired 80 contour to the entire thigh of the wearer of the garment, and more particularly to the front portion of the thigh where the flattening effect is especially produced. Furthermore in some instances the desired flattening 85 effect may be obtained by the employment of the hose supporter strap 17, as herein shown and described, without the use of the tension strap. That is to say, in instances where the flattening effect is not desired at 90 the waist line and where the supporting effect is not necessary the hose supporter strap attached as hereinbefore described may be employed without the tension strap for controlling the configuration given the 95 thigh of the wearer by producing the desired flattening effect in the front portion thereof.

I claim as my invention:

1. In an apparel corset and at each side 100 of the front steels thereof, an elastic tension strap secured at one edge adjacent the front steels and at the opposite edge to the body of the garment distant from the front steels to produce a flattening effect at the 105 waist line and to act as a support for the underlying parts of the body of the wearer between the waist line and the groin, and tension devices secured to the body of the garment at approximately the lower edge of the 110 tension strap and extending downwardly to produce a continued flattening effect from the waist line to the lower edge of the body of the garment.

2. In an apparel corset and at each side of 115 the front steels thereof, an elastic tension strap secured at one edge adjacent the front steels and at the opposite edge to the body of the garment distant from the front steels to produce a flattening effect at the waist line 120 and to act as a support for the underlying parts of the body of the wearer between the waist line and the groin, and a tension device secured to the body of the garment adjacent the lower edge of the tension strap 125 and extending downwardly therefrom to cause a lower edge of the tension strap to fit into the groin of the wearer, thereby providing an additional support therefor.

3. In an apparel corset and at each side of 130

the front steels thereof, an elastic tension strap secured at one edge adjacent the front steels and at the opposite edge to the body of the garment distant from the front steels to 5 produce a flattening effect at the waist line and to act as a support for the underlying parts of the body of the wearer between the waist line and the groin, and a tension device secured to the body of the garment 10 a slight distance above the lower edge of the tension strap and extending downwardly to cause the lower portion of the tension strap to extend into the groin of the wearer and to produce a continuous flattening effect 15 from the waist line to the bottom edge of the garment.

4. In an apparel corset and at each side of the front steels thereof, a tapering elastic tension strap secured along its longest edge 20 to the corset adjacent the front steel section thereof and at its opposite edge along a line distant from the front section to produce a flattening effect at the waist line, causing the upper end of the corset steel to be forced 25 away from the body of the wearer and providing a support for the underlying parts of the body of the wearer between the waist line and the groin, a hose supporter strap secured to the body of the garment along 30 a line slightly above the lower edge of the tension strap, and a hose supporter connected to the lower end of the hose supporter strap and the lower edge of the garment whereby the tension applied by the hose 35 supporter strap causes the lower edge of the

tension strap to extend into the groin of the wearer and provides a continued smooth flattening effect from the waist line to the lower edge of the garment.

5. In an apparel corset and at each side 40 of the front steels thereof, a tapering elastic tension strap secured along its longest edge to the corset adjacent the front steel section thereof and at its opposite edge along a line distant from the front section to produce a 45 flattening effect at the waist line, causing the upper end of the corset steel to be forced away from the body of the wearer and providing a support for the underlying parts of the body of the wearer between the 50 waist line and the groin, a hose supporter strap secured along its upper edge to the body of the garment along a line slightly above the lower edge of the tension strap and also for a predetermined distance along 55 its edge distant from the front steels, with the edge adjacent the front steel free from attachment to the garment, and a hose supporter attached to the lower edge of the corset and also to the lower edge of the hose 60 supporter strap whereby tension applied to the hose supporter strap causes the lower edge of the tension strap to fit into the groin of the wearer and also produces a continued smooth flattening effect from the waist line 65 to the lower edge of the garment.

Signed by me this 23rd day of April, 1920.

DANIEL KOPS.
